UNITED STATES PATENT OFFICE.

HERMAN A. FEIGELMAN, OF PATERSON, NEW JERSEY.

DESIGN FOR A DESK ACCESSORY.

Application filed January 30, 1928. Serial No. 25,085. Term of patent 14 years.

To all whom it may concern:

Be it known that I, HERMAN A. FEIGELMAN, a citizen of the United States, residing at Paterson, in the county of Passaic and State of New Jersey, have invented a new, original, and ornamental Design for a Desk Accessory, of which the following is a specification, reference being had to the accompanying drawing, forming part thereof.

The drawing shows my new design in perspective, viewing the same from the front.

I claim:

The ornamental design for a desk accessory, as shown.

In testimony whereof I affix my signature.

HERMAN A. FEIGELMAN.
